UNITED STATES PATENT OFFICE

105,160

DESIGN FOR A LEVER HANDLE

Roy H. Zinkil, Oak Park, Ill., assignor to Crane
Co., Chicago, Ill., a corporation of Illinois

Application October 29, 1936, Serial No. 65,574

Term of patent 14 years

To all whom it may concern:

Be it known that I, Roy H. Zinkil, a citizen of the United States, residing at Oak Park, in the county of Cook and State of Illinois, have invented a new, original, and ornamental Design for a Lever Handle, of which the following is a specification, reference being had to the accompanying drawing, forming part thereof.

Fig. 1 is a perspective view of the lever handle showing my new design.

Fig. 2 is a top plan view.

Fig. 3 is a side view.

Fig. 4 is an end view.

I claim:

The ornamental design for a lever handle, substantially as shown.

ROY H. ZINKIL.
